(57) **CLAIM**

The ornamental design for a modular hydrogen fuel cartridge, as shown and described.

DESCRIPTION

FIG. 1 is a top view of a modular hydrogen fuel cartridge showing our new design;

FIG. 2 is a bottom view of a modular hydrogen fuel cartridge showing our new design;

FIG. 3 is a left side view of a modular hydrogen fuel cartridge showing our new design;

FIG. 4 is a front side view of a modular hydrogen fuel cartridge showing our new design;

FIG. 5 is a right side view of a modular hydrogen fuel cartridge showing our new design; and,

FIG. 6 is a back side view of a modular hydrogen fuel cartridge showing our new design.

In the drawings, the broken lines shown represent unclaimed subject matter only and form no part of the claimed design.
